Inventor.

United States Patent Office.

ELKANAH BATEMAN, OF FREDERICK, MARYLAND.

Letters Patent No. 65,789, dated June 18, 1867.

IMPROVEMENT IN FLOUR-BOLTS.

The Schedule referred to in these Letters Patent and making part of the same.

TO ALL WHOM IT MAY CONCERN:

Be it known that I, E. BATEMAN, of Frederick, in Frederick county, and State of Maryland, have invented a new and useful Improvement in "Flour-Bolting Machines;" and I do hereby declare that the following is a full, clear, and exact description thereof, reference being had to the accompanying drawing, and to letters of reference marked thereon, forming part of this specification, and in which—

Figure 1 represents a vertical longitudinal section, and

Figure 2 a vertical transverse section of a bolting machine embracing my improvement.

The same letters of reference occurring on both figures indicate like parts.

This invention relates to that class of bolting machines wherein a revolving bolting-cylinder is used in combination with a fan arranged to revolve within said bolting-cylinder, and in the opposite direction from its rotation, and in which the flour, when driven by the force of the blast against the inner side of the bolting-cloth, is apt either to stick thereto, or, as the bolting-cylinder rotates, to roll around on the lower side of the horizontal cylinder, to be but slightly affected by such blast; and it consists in the application of a series of buckets or ribs within the bolting-cylinder, so arranged as to elevate such portion of the flour as may accumulate at the lower side of the cylinder, and, in its continuous rotation, to deliver it at a point above the level of the axis of the fan, to be again separated and driven towards and through the bolt.

To enable others to make and use my invention, I will describe it by referring to the drawing, in which A represents the casing of my apparatus, which may be made of sheet iron, wood, or other suitable material, and at either end is provided with bearings *a*, to support the journals of the shaft *B* of the fan *C*, which is rotated by means of a pulley, *D*, driven by any suitable motor. The bolting-cylinder *E* consists of the ordinary annular rims *b*, one at each end, and longitudinal ribs *e'* connecting them, which serve to support the bolting-cloth *d*, represented in the drawing in red lines. Four or more buckets or inwardly-projecting ribs *n* are attached to the inside of the bolting-cylinder, parallel with and connected to the ribs *e'* of the cylinder. The cylinder thus constructed is supported by radial arms *e e'*, those marked *e* being located a short distance within the end of the bolting-cylinder, to admit of the entrance of the feed-spout *F* within the end thereof, whilst those marked *e'* are connected with the opposite end of the said cylinder by brackets *f*, so as to admit of the extension of the fan-blades beyond the end of the bolt. These radial arms *e e'* are attached to collars or sleeves *g g'*, encompassing the shaft *B* of the fan. The sleeve *g'*, extending through, and outside of, the casing *A*, has attached to it a pulley or drum, *G*, by which the bolting-cylinder is rotated. The casing *A*, around and beneath the bolting-cylinder, is divided, in a transverse vertical direction, into two or more compartments, to form receptacles for the different grades of flour bolted, and is provided with an aperture, *h*, for the admission of air to the fan *C*, and which is regulated by a slide, *i*.

The operation will then be as follows: The grist being supplied to the bolting-cylinder through the spout *F*, the cylinder is put in motion, at the rate of about twenty-eight revolutions per minute, by means of a belt or other motor applied to the drum *G*; and the fan *C* being rotated at a velocity of from one to two hundred revolutions in the opposite direction to the motion of the cylinder *E*, a strong blast is created by the fan forcing the grist against the bolting-cloth; and by the rapid rotation of the fan, its one end being within the bolting-cylinder, and its other protruding beyond it, a strong current is created through the central portion, which may be regulated by adjusting the sliding door *i*, and by which current of air the fuzz on the end of the grain, the bran, and every particle lighter than the flour is carried forward and expelled. A radial blast is also caused by the fan, which, together with the longitudinal current of air just named, causes an even distribution of the grist throughout the length of the bolting-cylinder; and, as the said cylinder rotates, that portion of the grist which may have settled in the lower portion of the cylinder is elevated by the buckets *n* until they successively reach a position somewhat above the level of its axis, and is again discharged towards the centre by its own gravity, to be acted on by the blast of the fan as before. If it is desired to bolt various grades of flour, the bolting-cylinder is constructed with sections of its length covered with different grades of canvas, and the chamber enclosing it divided into compartments correspondingly.

Having thus described my invention, what I claim as new, and desire to secure by Letters Patent, is—

The buckets *n*, arranged and operating in combination with the bolting-cylinder and fan, substantially as herein set forth.

In testimony whereof I hereunto subscribe my name before two subscribing witnesses this 18th day of January, 1867.

E. BATEMAN.
